(57) **CLAIM**

The ornamental design for a wood chipper knife as shown and described.

DESCRIPTION

FIG. 1 is a perspective view of a wood chipper knife showing a first embodiment of my new design;

FIG. 2 is a right side view thereof;

FIG. 3 is a left side view thereof;

FIG. 4 is a front view thereof;

FIG. 5 is a rear view thereof;

FIG. 6 is a top plan view thereof; and

FIG. 7 is a bottom plan view thereof;

FIG. 8 is a perspective view of a wood chipper knife showing a second embodiment of my new design;

FIG. 9 is a right side view thereof;

FIG. 10 is a left side view thereof;

FIG. 11 is a front view thereof;

FIG. 12 is a rear view thereof;

FIG. 13 is a top plan view thereof; and

FIG. 14 is a bottom plan view thereof;

FIG. 15 is a perspective view of a wood chipper knife showing a third embodiment of my new design;

FIG. 16 is a right side view thereof;

FIG. 17 is a left side view thereof;

FIG. 18 is a front view thereof;

FIG. 19 is a rear view thereof;

FIG. 20 is a top plan view thereof; and

FIG. 21 is a bottom plan view thereof;

FIG. 22 is a perspective view of a wood chipper knife showing a fourth embodiment of my new design;

FIG. 23 is a right side view thereof;

FIG. 24 is a left side view thereof;

FIG. 25 is a front view thereof;

FIG. 26 is a rear view thereof;

FIG. 27 is a top plan view thereof; and,

FIG. 28 is a bottom plan view thereof.
